WIG STYLING TRAY

James B. Little, 2809 W. Camille,
Santa Ana, Calif. 92704

Filed Sept. 11, 1968, Ser. No. 13,501

Term of patent 14 years

Int. Cl. D28—03

U.S. Cl. D86—10

FIGURE 2

I claim:

The ornamental design for a wig styling tray, as shown.
